UNITED STATES PATENT OFFICE.

HERBERT C. COLBURN, OF VICTOR, COLORADO.

FEEDING APPARATUS.

1,149,426.

Specification of Letters Patent. Patented Aug. 10, 1915.

Original application filed March 3, 1914, Serial No. 822,176. Divided and this application filed June 29, 1914.
Serial No. 847,926.

To all whom it may concern:

Be it known that I, HERBERT C. COLBURN, a citizen of the United States, residing at Victor, in the county of Teller and State of Colorado, have invented certain new and useful Improvements in Feeding Apparatus, of which the following is a specification.

My invention relates to improvements in feeding apparatus used in the treatment of metalliferous ores, and more particularly to apparatus of the character shown and described in my application for patent, Serial No. 822,176, filed March 3, 1914, of which the present application is divisional.

My improved apparatus is particularly adapted for use in feeding zinc dust in the process of precipitating gold from gold-bearing cyanid solutions, in which zinc is used as a precipitant. In the practice of this process it is of paramount importance that the zinc is introduced into the solution in a thoroughly emulsified condition and in measured quantities which vary in accordance with the richness of the solution and the rate at which it is fed to the filter press.

With this object in view, my invention consists of an association of coöperative devices by which the desired quantities of zinc dust are automatically measured off and delivered in a thoroughly emulsified condition to the apparatus in which the precipitation process is carried on.

The devices hereinbefore referred to, include a feeding element which operates intermittently to dispense determinate quantities of zinc dust or other material in determinate periods from a supply contained in a receptacle with which the element is connected. These measured quantities are delivered into a bowl from which they are discharged by a flow of liquid, preferably consisting of the solution used in the precipitation process, which insures the passage of every particle of the measured quantities to the element of my invention in which the dust is emulsified. The quantities of dust before entering the emulsifying mill are permitted to accumulate in a feeding device which delivers the material at a rate which insures of a continuous and uniform discharge of the emulsion from the mill after the material fed thereinto has been thoroughly subjected to its grinding and emulsifying actions.

By the coöperation of the different ele-

ments of my invention, the exact quantities of zinc dust required for the proper operation of the filter press in precipitating the gold in the solution, are first of all automatically measured off, they are subsequently delivered to the emulsifying mill through the instrumentality of the feeding devices which are designed to prevent clogging and adhesion, and the material is delivered from the mill to the filter press in the emulsified condition which is one of the most essential requirements in the effective operation of the precipitation process. In this connection it should be understood that ordinary agitation is not sufficient to produce an emulsion of the character required, but that a combined grinding and emulsifying action such as that which takes place in a pebble mill of the type hereinafter to be described, is necessary to provide an emulsion in which the zinc dust is so evenly and finely divided that it will remain indefinitely in solution.

An embodiment of my invention has been shown in the accompanying drawings in the various views of which like parts are similarly designated, and in which,

Figure 1 is a sectional elevation of the improved apparatus, and Fig. 2, a section taken on the vertical planes of the axes of the screw-conveyer and the emulsifying mill comprised in my invention.

Referring more specifically to the drawings, the reference numeral 2 designates a suitable supporting structure upon which is mounted a supply bin 3 which in the operation of the apparatus is filled with zinc dust or other material. The bin has a vertical side 4 and opposite thereto a slanting wall 5 which at its lower end is bent to provide an open trough 6 in which a feed screw 7 is mounted for rotation. In the operation of the apparatus the screw is intermittently rotated by means of a friction ratchet 8 applied at an end of its shaft which projects through an opening in the closed end of the trough, opposite to that which is open for the discharge of the material transported by the screw. The ratchet which may be of any suitable construction, includes an oscillating member 9 which by means of a longitudinally extensible pitman 10 is operatively connected with the wrist of a crank wheel 12 which by means of suitable transmission gearing 13, is driven from a line

- shaft 14 which is mounted in bearings on the supporting structure and carries a pulley 115 for its connection with an engine or other motive agent. The pitman is connected with the oscillating element by means of a collar 15 which being fastened by a set screw, may be readily adjusted to vary the intermittent movements of the transport screw in accordance with the quantities of material it is required to deliver to the emulsifying element of my invention during a finite period. The material discharged by the action of the screw at regular intervals through the open end of the trough, falls into a bowl 16 in which it is subjected to the action of a small stream of liquid, preferably the solution used in the precipitation process, which being ejected into the bowl through a nozzle 17 agitates the pulverous substance and washes it through a conduit 18 into a feed box 19 from which it is removed into a rotary cylindrical pebble mill 20 at a determined rate, by the rotary movement of a scoop 21.
- 5 The mill is mounted in bearings on the supporting structure by means of two axially alined, hollow trunnions 22 and 23, and it is driven from the line shaft by means of a sprocket chain 24. The scoop is fixed 15 at the end of the hollow trunnion 23 to rotate in unison with the mill and it serves to deliver the material into the cylinder at regular intervals and in measured quantities.
- 10 The quantities of zinc dust fed into the mill during a determined period, are determined by the capacity of a scoop and the rate of velocity at which the cylinder rotates, so that there will be a continuous, uniform discharge of emulsion from the mill 20 after the material has been thoroughly subjected to the grinding and emulsifying action of the mass of small flint pebbles 25 with which the cylinder is approximately 15 one-third filled.
- 15 The mill is during its rotary movement, supplied with barren solution in quantities required to produce the emulsion which may be discharged through the hollow trunnion 22 opposite to that with which the scoop is connected, by the suction of the filter press.

pump usually operated in the practice of the precipitation process hereinabove referred to.

It will be understood that while I have shown and described my invention in the best form at present known to me, the apparatus is susceptible of variations without any material deviation from the true principle and nature of the same. 60

Having thus described my invention what I claim and desire to secure by Letters-Patent is:

1. Apparatus for feeding a precipitant in a system of precipitating metals from solutions, comprising an emulsifying mill adapted for the discharge of material at a uniform rate, a receptacle, a device operating to intermittently convey measured quantities of material from said receptacle to the 70 said mill, means for feeding a liquid to the receptacle, and means to intermittently supply to the liquid fed into the receptacle, a powdered precipitant in uniform measured quantities. 75

2. Apparatus for feeding a precipitant in a system of precipitating metals from solutions, comprising an emulsifying mill adapted for the discharge of material at a uniform rate, a receptacle, a device operating to 80 intermittently convey measured quantities of material from said receptacle to the said mill, a bowl discharging into the receptacle, means for supplying a liquid to the bowl, and means for feeding intermittently into 85 the bowl, a powdered precipitant in uniform measured quantities.

3. Apparatus for feeding a precipitant in a system of precipitating metals from solutions, the combination with an emulsifying 90 mill, of an appliance operating to intermittently convey measured quantities of material to the said mill, and means for feeding to the said appliance, a powdered precipitant intermittently in uniform quantities. 95

In testimony whereof I have affixed my signature in presence of two witnesses.

HERBERT C. COLBURN.
